OUTER JACKET OF CRYOGENIC STORAGE VESSELS

Lloyd E. Anderson, Jr., Pittsburgh, Pa., and John O. Cliff, Ellington, Conn., assignors to Pittsburgh-Des Moines Steel Company, Pittsburgh, Pa.

Filed Sept. 29, 1971, Ser. No. 184,982

Term of patent 14 years

Int. Cl. D23—01
U.S. Cl. D23—2

FIG. 1.

FIG. 2.

FIG. 4.

FIG. 3.

FIG. 1 is a front elevational view of the outer jacket of cryogenic storage vessels, showing our new design;

FIG. 2 is a cross sectional view taken on line 2—2 of FIG. 1 looking in the direction of the arrows;

FIG. 3 is a cross sectional view taken on line 3—3 of FIG. 1 looking in the direction of the arrows; and

FIG. 4 is a cross sectional view taken on line 4—4 of FIG. 1 looking in the direction of the arrows.

We claim:

The ornamental design for an outer jacket of cryogenic storage vessels, as shown.
